(57) **CLAIM**

The ornamental design for a cooling module, as shown and described.

DESCRIPTION

FIG. 1 is a perspective view of a cooling module according to a first embodiment of our new design;

FIG. 2 is a top plan view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is perspective view thereof shown in the environment of a cooling module housing,

FIG. 8 is a perspective view of a cooling module according to a second embodiment of our new design;

FIG. 9 is a top plan view thereof;

FIG. 10 is a front elevation view thereof;

FIG. 11 is a rear elevation view thereof;

FIG. 12 is a right side elevation view thereof;

FIG. 13 is a left side elevation view thereof; and,

FIG. 14 is perspective view thereof shown in the environment of a cooling module housing.

The broken lines shown herein for illustrative purposes of the environment of the cooling module housings in FIGS. 7 and 14 form no part of the claimed design.
